UNITED STATES PATENT OFFICE.

JOHN ROGERS, OF NEW CANAAN, CONNECTICUT.

DESIGN FOR A GROUP OF STATUARY.

SPECIFICATION forming part of Design No. 12,484, dated September 20, 1881.

Application filed August 15, 1881. Term of patent 14 years.

To all whom it may concern:

Be it known that I, JOHN ROGERS, a citizen of the United States, residing at New Canaan, in the county of Fairfield and State of Connecticut, have invented and produced a new and original Design for a Group of Statuary, of which the following is a specification, reference being had to the accompanying photographs, forming part thereof.

10 The group consists of five figures arranged on and about a balcony and the steps leading thereto. The name on the base is "The Wrestlers." The design is taken from Shakespeare's play of "As You Like It," and represents Rosalind, Celia, and Touchstone watching the wrestling-match between Orlando and Charles. The two ladies are standing on the balcony and looking down on the contest. The smaller one is resting her right hand on the railing, and her

one. Touchstone is partly seated on the lower part of the railing. His right leg is on the newel-post, and held at the ankle by his left hand. He is dressed in a fool's costume, with points and bells. In the foreground is Charles 25 the Wrestler with only trunk-breeches and sandals on. Behind him is Orlando, who has dexterously turned Charles around, so as to get behind him, and, with his arms round his waist, has lifted and is about to throw him. 30

I claim—

The design for a group of statuary herein shown and described, consisting of five figures, representing the wrestling-scene in Shakespeare's play of "As You Like It."

JOHN ROGERS.
